UNITED STATES PATENT OFFICE

2,670,701

SHOE SEWING MACHINE

Fred Ashworth, Wenham, and Joseph R. Ioannilli, Boston, Mass., assignors to United Shoe Machinery Corporation, Flemington, N. J., a corporation of New Jersey

Application March 3, 1949, Serial No. 79,484

59 Claims. (Cl. 112—38)

1

The present invention relates to sewing machines intended primarily for the manufacture of shoes and more particularly to improvements in a hook needle lockstitch machine of the McKay type having a rotary shoe entering horn. Illustrative machines of this type are disclosed in United States Letters Patent No. 1,885,927, granted November 1, 1932 on application of B. T. Leveque and No. 2,331,118, granted October 5, 1943 on application of J. Gouldbourn et al. and in an application for United States Letters Patent Serial No. 732,903, filed March 6, 1947 in the name of H. Boothroyd (now United States Letters Patent No. 2,525,858, granted October 17, 1950).

The machines of the patents above referred to, in addition to a hook needle, have a shuttle or loop taker at the same side of the work as the needle and, at the opposite side of the work, a take-up and a needle threading device within the tip end of the rotary horn. In the Gouldbourn machine thread measuring mechanism also is provided for pulling from the supply an amount of thread sufficient for each stitch. In order to enable the needle to be threaded and withdrawn from the work without causing injury to the thread as a result of sliding movement of the thread in the needle hook, particularly as the threaded hook is moving through a tight fitting perforation in the work operated upon by the patented machines, the needle loop of each stitch formed previously to the one in process of formation is left untightened and is contracted to provide one side of the expanding needle loop for the stitch in process, the other side of the loop being provided by the take-up or thread measuring mechanism. During the withdrawal stroke of the needle from the work the previous needle loop is contracted by drawing along the underside of the work the thread connecting the stitch then being formed and the stitch previously formed. Ordinarily, the portion of the undersurface of the work along which the connecting thread lies is engaged by the end of the horn so that any substantial pressure of the work on the horn tends to grip the connecting thread and to cause irregularities in the frictional drag thereon as the previously formed needle loop is being contracted. These irregularities are a troublesome cause of faulty or non-uniform stitches.

To avoid substantial pressure of the work on the horn along the undersurface engaged by the connecting thread in prior machines, the work is clamped on the horn by a presser foot acting along the edge only of the horn end opposite the

2

connecting thread and often the clamping action of the presser foot is relieved at critical times to enable the thread to slide freely between the work and the horn.

5 To feed the work after each needle loop is drawn through the work a feed point or awl is provided in the prior machines, acting on the work along the line of feed between the presser foot and the point of needle operation to pierce 10 the work a stitch length ahead of the point of needle operation and to carry the perforation formed by the feed point or awl into line with the needle path. Accordingly, it is possible to clamp the work no closer to the needle than the 15 length of a stitch so that sufficient space for the awl or feed point is maintained. For this reason also the work is clamped along one edge only of the work engaging end of the horn and in some instances when long stitches are being sewn 20 the presser foot must be located entirely beyond the edge of the horn end. It is therefore necessary for the operator of the prior machines to hold the work more securely against tilting movement on the horn than would be required if a 25 better work clamping action were provided by locating the presser foot directly opposite the work engaging end of the horn.

It is an object of the present invention to simplify the construction and to improve the 30 mode of operation in a shoe sole sewing machine of the type above referred to and to so arrange the work clamping and feeding devices that a shoe being operated upon may be presented to the sewing devices and directed during operation 35 of the machine more easily than heretofore and in a manner which will be conducive to accurate spacing of the stitches while retaining all of the advantages of thread handling procedures attainable in the prior patented machines. A further object of the invention is to provide a novel and effective construction of McKay type shoe sewing machine capable of operation at high speeds, in which the visibility at the point of sewing operations is greater than in machines of similar construction and in which the parts are less subject to breakage, wear, irregularity in operation or the necessity of frequent adjustment.

In its preferred form the machine constructed 40 according to the features of the present invention, includes a hook needle and a presser foot at one side of the work and a rotary shoe entering horn at the other side of the work, in which the needle is actuated to withdraw its threaded hook from the horn into the substance of a shoe

sole or other work and thereafter to be shifted the length of a stitch while still engaging the sole to feed the shoe sole. With such an arrangement it is possible to locate the presser foot directly over that portion of the sole engaged by the end of the horn so that firm clamping action is obtained during the formation and setting of each stitch. By actuating the needle to shift the shoe a stitch length after being withdrawn from the horn the thread of each stitch being formed is acted upon the same distance from the point of clamping engagement of the presser foot as in prior machines except that the connecting thread between the stitch in process of formation and the previous stitch is further away from the center of the horn than heretofore by a stitch length. As a result, there is less tendency to clamp the thread connecting the last two stitches between the work and the horn and consequently to insert irregular stitches. Another advantage of such arrangement is that it enables a large sized shuttle or loop taker for forming lock stitches to be located at the side of the needle with the completed stitches of the seam, particularly when the shuttle is employed to set each stitch as in the machines of the patent above referred to.

To relieve the strain of the work feeding needle as it penetrates the work, the shoe sole is pierced, in the illustrated machine, by an awl mounted for movement along the line of feed in fixed spaced relation to the needle. The awl in the illustrated machine serves only to pierce the sole against the support of the horn. To enable feeding movement of the needle to be adjusted conveniently, in this feature of the machine, the needle has imposed on it an idle lateral movement along the line of feed after it disengages the work. The needle is spaced along the line of feed a fixed distance from the awl more than the length of a stitch and the idle lateral movement of the needle makes up the difference between the length of the stitch and the spacing between the needle and awl. With such arrangement the feeding movement of the needle may be increased or decreased without necessitating a change in the fixed spacing distance between the needle and awl, as required in the machine of the Gouldbourn et al. patent.

In the patented machines it is necessary to employ a take-up for pulling each needle loop off the shuttle with its stroke sufficient to take up and give up thread in an amount corresponding with the size of the shuttle, the take-up requiring accurate timing and coordination with the movements of the shuttle. Accurate timing of the take-up with the movements of the shuttle in a rotary horn type of machine presents a difficult mechanical problem due to the lengths of the connections required to actuate the respective devices. The longer the connections the heavier they become and the greater are the effects of lost motion and yield in disturbing the accuracy of timing between the actuated devices. For like reason, the larger the shuttle the greater must be the movements of the take-up and the more difficult still are the coordination problems.

An important object of the invention therefore is to eliminate from a shoe sole sewing machine of the type under consideration, the usual take-up for pulling each needle loop off the shuttle, and even to avoid entirely the necessity of utilizing a regular take-up in this type of machine. With the elimination of such a take-up the problem of coordinating and timing the operation of

the take-up accurately with relation to the movements of the shuttle no longer presents any difficulty. Accordingly, a shuttle may be employed which is large enough to carry the needle loop about a locking thread supply of any desired capacity within practical limits. To this end, the machine of the present invention is equipped with a multiple beak shuttle or loop taker acting to draw each loop of thread through the work while a previously formed loop of thread is retained on another beak of the shuttle. The use of a multiple beak shuttle enables the loop previously formed to be controlled while being contracted at a rate determined by the extension of the succeeding loop, the thread being drawn from the previously formed loop through the work and along the undersurface of the work where it engages the horn. In this way the shuttle or loop taker acts as its own take-up.

In the operation of the shuttle in the present machine, each beak is brought into position for reception of a loop of thread in regular sequence. For this purpose the illustrated shuttle is driven by a gear train at a rate less than one complete rotation during each sewing cycle and in order to coordinate the movements of the shuttle with the other stitch forming devices, in this feature of the machine, a variable speed device is employed in the gear train to accelerate the shuttle as each beak receives its loop and to decelerate the shuttle thereafter. The use of a variable speed device is particularly effective in a hook needle sewing machine to enable proper timing of the other stitch forming devices. Furthermore, this feature of the invention cooperates in an advantageous manner with the feature embodied in the needle feed since with the needle feed each stitch being formed is carried away from the end of the horn where the work clamping pressure is being exerted and the pull on the thread exerted by the shuttle tends to lift the work and facilitate sliding movement of the thread along the underside of the work between the horn and the work. Also, if a shuttle of greater diameter than usual is employed the pull of the thread exerted thereby has a component which assists the feed and facilitates easy movement of the work through the machine.

While the two features of the invention relating to the needle feed and the multiple beak shuttle mutually contribute to the production of a particularly beneficial result when embodied in a McKay type rotary horn machine, these features are not so limited in their application but may be employed to advantage in other than horn type machines and in machines utilizing devices other than the needle for feeding the work and equipped with shuttles or loop takers other than those of the multiple beak type.

These and other features of the invention including novel means for controlling each needle loop as it is being disengaged from the shuttle, an improved form of thread case, a readily adjustable feed actuating mechanism, and a simplified and improved construction of needle and awl mounting as hereinafter described and claimed, will become apparent from the following detailed specification taken in connection with the accompanying drawings, in which

Fig. 21 is a similar view showing the positions of the parts after the needle has been disengaged from the work and moved idly along the line of feed to bring the awl into position to pierce the work;

Fig. 22 is a detail view in front elevation on an enlarged scale of the operating parts surrounding the sewing point, showing the positions of the parts just before the awl moves toward the work and indicating the path of the needle point with the feed mechanism adjusted for maximum feed;

Fig. 23 is a similar view of the same parts with the feed mechanism adjusted for reduced feeding movement and indicating the corresponding path of the needle;

Fig. 24 is a detail view of the thread measuring mechanism; and

Fig. 25 is a time chart indicating the manner of operation of the machine.

The illustrated machine is similar, except as

hereinafter pointed out, to the lockstitch McKay horn type shoe sewing machine disclosed in the patent to Gouldbourn et al., as modified by the construction described in the Boothroyd application, both identified above. Referring to the drawings, the machine is equipped with a curved awl 2 secured in the front end portion of an awl carrier 4 arranged to be moved vertically about a horizontal axis extending laterally of the machine, parallel to the line of work feed a short distance above the level of the work engaging surface on a work support comprising a rotary shoe entering horn 6 having a needle receiving opening 1 (see Fig. 2) and a needle threading device in the form of a whirl 8 (see Fig. 16) at the upper end of the horn in alignment with the opening 1 and with the needle. Mounted at the same side of the work concentrically with the axis of the awl is a needle carrier 10 at the front end of

which is secured a curved hook needle 12, the needle and awl being arranged with a fixed spacing along the line of feed at least the length of a stitch between them and movable laterally along the line of feed together. To clamp a shoe on the work engaging surface of the horn 6 a presser foot 14 is secured to the lower end of a sliding presser foot bar 16.

For actuating the presser foot, the bar 16 is connected to mechanisms for causing the foot to clamp the work securely against the horn while each stitch is being set, for locking the foot in work clamping position and for lifting the foot from engagement with the work. After the presser foot is locked, the clamping mechanism is unlocked and the foot is reengaged with the work with a yielding pressure. The means for actuating the bar 16 comprises cam actuated connections including a lever 17 having a forked horizontal arm surrounding a block 19 rotatably connected to the presser foot bar. The other cam actuated connections are the same as those more fully described in the patent to Gouldbourn et al. No. 2,331,118. The means for locking the presser foot while in clamping engagement with the work include a locking wedge 21 in the cam actuated connections described in the Gouldbourn et al. patent.

It has long been the desire to provide a rotary horn type McKay sewing machine with a work clamping presser foot which will engage a shoe sole and hold the sole in position on the work engaging surface of the horn by pressure applied directly opposite a portion of said work engaging surface, close to the path of and in advance of the sewing needle as it penetrates the work. The difficulty in such an arrangement is in providing space for the awl or feed point while moving it along the seam line in advance of the sewing point. If an attempt is made to move the presser foot out of the path of the awl or feed point during work feed, the presser foot actuating mechanism is correspondingly complicated.

According to an important feature of the present invention, mechanism is provided for shifting the needle and awl laterally in the line of feed during each sewing cycle in such a way that the awl serves only to pierce a shoe sole at a point in line with the needle receiving opening in the horn. After the awl is retracted the needle is shifted into alignment with the awl perforation and enters the needle receiving opening in the horn through the awl perforation where it receives a loop of thread. To feed the shoe the threaded hook of the needle is withdrawn lengthwise from the whirl 8 and from the opening in

the horn to clear the horn during lateral needle movement and is detained while engaging the shoe within the substance of the shoe sole as it is shifted laterally away from the needle receiving opening in the horn the length of a stitch.

The needle and awl carriers 4 and 10 are in the form of bowed arms provided with elongated hubs supported to oscillate about the same axis within tubular bearings 18 and 20, best shown in Figs. 16, 17 and 18. The outer ends of the bearings are clamped to the machine frame by bolts 22 (Fig. 2) and the bearing 18 has laterally extending ears between which is fulcrumed a fork ended feed lever 24 (see Figs. 19, 20 and 21). The fork end of the lever 24 surrounds a block 26 rotatably mounted on a pivot 28 clamped in one end of an eye-headed spindle 30 passing through the hubs of the needle and awl carrier arms 4 and 10, the arms being retained against relative movement lengthwise of the spindle. By this construction the needle and awl are mounted with a fixed spacing between each other along the line of work feed at a distance at least the length of the longest stitch which the machine is called upon to insert.

The mechanisms for actuating the feed lever 24 comprise a link 32 pivotally connected at 33 to the rearward arm of the feed lever. At its other end the link 32 is connected by a central pivot 34 to a pair of links 36 and 38. The link 36 comprises a part of an adjustable feed mechanism which imparts the actual work feeding movements to the needle. To provide adjustment for the feeding mechanism the link 36 has secured in it a bolt 40 clamped within an arcuate slot 42 in an arm 44 secured to a vertical shaft 46. The shaft 46 is rotatably mounted in the machine frame and in turn has secured to it a cam arm 48 provided with a roll 50 engaging a slot 52 in a cam 54. The cam 54 is fixed to a vertical cam shaft 56 rotating in unison with a main sewing shaft 58. The curvature of the arcuate slot 42 in the arm 44 is such that it is concentric with the central pivot 34 when the needle moves into alignment with the awl perforation and while the needle is in its fully fed position. When the bolt 40 is loosened and moved along the slot 42 it increases or decreases the effective length of the lower arm of lever 44 and varies the shifting movement of the needle while in engagement with the work.

After the needle has been withdrawn from engagement with the work with its loop of thread it is shifted idly with a lateral movement along the line of feed by an amount corresponding to that required to enable the awl to be moved into alignment with the needle opening in the horn. For this purpose the central pivot 34 is moved at the proper time substantially into alignment with the bolt 40 and the pivot 33 as in Fig. 21. This movement into alignment of the bolt and pivots occurs regardless of the position of the bolt 40 in the slot 42 so that the needle and awl always are enabled to enter the work at the same location above the needle receiving opening in the horn a stitch length from the previously formed perforation, the curvature of the slot 42 being again concentric to the pivot 34 at this time. Thus, with the bolt 40 adjusted in the slot 42 to a position at the outer end of the slot and with the cam levers 44, 48 in the positions of Fig. 21, so that the awl is moved into alignment with the needle opening in the horn, the path of the needle point describes an outline similar to that indicated at 60 in Fig. 22. The path 60 shows no idle

lateral movement of the needle and all of the lateral movement occurs while the threaded needle hook is detained within the substance of the work in the form of a shoe sole 62. If the bolt 40 is adjusted to an intermediate position as in Fig. 21 along the slot 42 the path of the needle point will be similar to that indicated at 64. In moving along this path the needle withdraws from the opening in the horn, is detained along the portion 66 of the path, is withdrawn from the sole 62 and is shifted idly along the seam line out of engagement with the sole through the portion 68 of the path 64 to bring the awl into alignment with the needle opening in the horn for a new stitch. The length of the slot 42 is made sufficient to take care of the maximum desired length of stitch.

For maintaining the needle and awl carriers with a uniform fixed spacing between each other along the line of feed, adjacent faces of the needle and awl carrier arms are retained in engagement with each other and the hubs of the arms are cut away to receive a perforated spacer 70 having radial openings 72 (see Figs. 17 and 18). The spacer is mounted on the spindle 30 and has laterally projecting lugs 74 entering slots in a pair of sleeves 76 and 77 disposed between the spindle 30 and the hubs of the carrier arms 4 and 10. The sleeve 76 is internally threaded to engage threads formed near the eye-headed end of the spindle 30. The other end of the spindle is threaded for a pair of check nuts 78 which act to clamp the two sleeves against the spacer and retain the spindle, sleeves and spacer in fixed position relatively to each other. The sleeves 76, 77 also are provided with flanges at their outer extremities, engaging loosely with the hubs of the carrier arms, so that when the sleeves are clamped against the spacer the carrier arms are free to turn. When the check nuts 78 are loosened the threaded sleeve 76 may be rotated by engaging a pin wrench within one of the radial holes in the spacer, thus changing the alignment of the needle and awl with the opening in the end of the horn 6.

To actuate the needle and awl toward and from the horn to cause the awl to pierce the work and the needle to enter the awl perforation, the needle and awl carrier arms 4 and 10 are formed with laterally projecting lugs 80, 82 engaged by radial slots projecting from the hubs of a pair of cam levers 84 and 86. The hubs of the cam levers 84 and 86 are rotatably mounted on the outside surfaces of the bearings 18 and 20, respectively. The cam levers have rolls engaging slots at opposite sides of a cam 88 secured to the main sewing shaft 58. The arrangement of the lugs 80 and 82 in the slots of the levers 84 and 86 enables the carrier arms to move laterally in the direction of feed while being actuated toward and from the horn.

To reinforce the needle against the lateral thrust of the work while the needle is shifted to feed the work, the needle is acted upon close to its point of engagement with the work by an arm 89 through which passes a stud 90 rotatably mounted in the needle carrier arm 10. The arm 89 is formed in two parts secured together, in one of which the stud 90 is secured and which has an upwardly projecting finger slidably engaging the left side of the needle carrier arm 10. The other part of the arm 89 has a forwardly projecting portion engaging the needle on the right side and moves along the needle during entry of the needle into the work. The needle engaging

arm is yieldingly maintained in a position close to the needle hook while the needle is disengaged from the work. To hold the needle engaging arm 89 in this position the arm is connected by a tension spring 92 stretched between the arm and the needle carrier arm 10. To limit the movement of the needle engaging arm 89 it carries a set screw 94, the head of which engages the carrier arm 10 when the needle is disengaged from the work. As the needle approaches the work, the arm 89 contacts a step surface 95 (see Figs. 22 and 23) on the presser foot 14 which holds the arm 89 stationary during the continued work entering movement of the needle.

As has been stated, the illustrated machine is equipped at the side of the work with the needle, with a multiple beak shuttle or loop taker, best shown at 98 in Figs. 6 and 7. The shuttle 98 has four beaks formed by slots cut between driving teeth 100 about the outside circular edge of the shuttle. The formation of the slots between the teeth constitutes what is commonly known as a "deep tooth shuttle or loop taker" and enables the thread in a needle loop passing over the shuttle to ride beneath the teeth of a driver gear 102 (Figs. 3 and 4) engaging the teeth 100 on the shuttle without contacting the driver gear. The multiple beaks on the shuttle enable one beak to receive a loop of thread from the needle while another beak retains control of the previously formed loop of thread in regular sequence.

The shuttle 98 is of a size substantially larger than those employed in the patents above referred to, so that a much greater than usual quantity of locking thread may be contained within a locking thread supply case 103 about which the shuttle carries each needle loop. The shuttle is arranged to be rotated less than a complete revolution during each sewing cycle through a speed reducing gear train, described more fully hereinafter, with a driving ratio proportional to the number of beaks on the shuttle less one, to the whole number of beaks. By so doing each beak is brought to a position for reception of a loop of thread from the needle successively. Thread for the loop being extended by the shuttle during formation of each stitch also will draw from the loop of thread previously formed and being carried down from the top of the shuttle where it already has passed a position of maximum extension.

The operation of the shuttle in drawing thread from a previous needle loop into a stitch which is in the process of being formed with its loop being extended is illustrated in Figs. 12 to 15, inclusive. In these figures a needle loop 104 of a stitch in the process of being formed is extended sufficiently to engage a beak of the shuttle in Fig. 12. The preceding loop of the previously formed stitch is indicated at 106 and is contracted somewhat from the position of maximum extension after passing the high part of the shuttle but the loop 106 is still retained, by means to be described, from disengagement with the shuttle. As the loop 104 in process is being enlarged (Fig. 13) the preceding loop 106 is contracted still further by movement of the thread upwardly through the work, along the undersurface of the work in that portion 108 of the thread passing between the stitch being formed and the previously formed stitch. During this time the awl 2 starts to move downwardly toward the work and in Fig. 14 is shown after the work has been pierced and the awl has started to be withdrawn. When the position of the shuttle of Fig. 14 is

reached the preceding needle loop 106 is contracted sufficiently to escape from its beak on the shuttle and after the position of Fig. 15 is reached the preceding needle loop is tightened and drawn into the work to set the stitch by the still enlarging loop 104 of thread as it reaches the position of maximum extension on the shuttle. Thereafter the loop 104 passes diametrically across the center of the shuttle and surrounds the supply of locking thread to complete the formation of the stitch in process.

The manipulation of each needle loop, while forming and setting a stitch, take place with a minimum of movements in the thread through 15 the horn particularly while each needle loop is being passed over the thread supply case by the shuttle. Thus, the time of engagement of the thread over guide members in the horn and through the work engaging the end of the horn is substantially reduced and is less than in machines of the patents noted above in which a take-up is employed to draw each needle loop from the shuttle. The principal thread movement in the present machine occurs only in the 20 loops of thread engaging the shuttle so that no take-up action is required to control the thread for the shuttle.

To enable each new loop of thread to be drawn through the work by the needle, the forward side 30 of each loop, as it is drawn through the work by the needle, is furnished from the contracting previously formed looped of thread and the other side of the new loop is furnished from the supply payed out through the horn so that no sliding movement occurs at any time in the needle hook. The amount of thread payed out through the horn in the illustrated machine is sufficient 35 only to furnish thread for the supply side only of each needle loop before the needle reaches the top of its stroke, thread required for spreading each needle loop being furnished from the preceding contracting needle loop.

To enable thread for the supply side of each 40 needle loop to be payed out from the horn while the threaded needle is being drawn through the work, a thread controller is located below the mounting for the horn. Referring to Fig. 1, the thread controller comprises an arm of a bell crank lever 110 fulcrumed on a shaft 112. A second arm of the thread controller lever 110 is connected to a link 114, in turn connected to a cam lever 116. The cam lever 116 has a roll 45 engaging a cam on a shaft 118, corresponding to the shaft 31 of Patent No. 2,331,118. The shaft 31 of Patent No. 2,331,118 is identified in that patent as a take-up actuating shaft and is arranged to actuate a take-up for giving up and taking up thread in full amount for the passage of each needle loop about the shuttle. For that 50 purpose, the mechanism actuated by the shaft of the patent moves its take-up arm through a relatively large stroke. The present thread controller 110 is distinguishable from the take-up in the said prior patent by the relatively short 55 full stroke of the present controller which is sufficient only to furnish less than half the thread needed from the time the needle is threaded until it reaches the top of its stroke at the end of its movement away from the work. Thereafter, the thread yielding movement of the controller is terminated.

In order to retract the thread payed out by the thread controller after the threaded needle has withdrawn from the work so that the controller may again pay out a similar length of

thread for the needle stroke of the succeeding stitch, the illustrated thread controller 110 is actuated to retract thread as soon as a shuttle beak engages a spread loop and the needle is disengaged therefrom. The thread retracting movement of the thread controller takes place during the time each loop of thread moves from its position of engagement with the shuttle (Fig. 12) to a position of maximum extension (Fig. 15) about the shuttle and thread case. Thus, the retracting movement of the illustrated thread controller is relatively short as compared with a full scale taking up action required by the take-up arm of the patented machine, all the thread required by the enlarging loop engaged by the shuttle in the present machine being drawn from the preceding loop 106 of thread, contracting it until it is drawn into the work and until the stitch formed thereby is set (Feb. 15).

To open each loop of needle thread for the shuttle the machine is provided with a loop spreader 120 (see Figs. 2 and 12). The spreader 120 is in the form of an angular arm projecting downwardly and forwardly from a diametrically arranged socket 121 at the left end of a spreader shaft 122 within which socket the spreader is clamped. The forward end of the spreader is forked and arranged to engage the side of the loop carried by the needle which extends to the preceding loop of thread on the shuttle. Accordingly, when the spreader engages the thread it draws thread from the preceding loop and not from the needle. Thus, it is unnecessary to provide thread from the horn to supply the needle loop while being spread.

The spreader shaft 120 is mounted at an angle to the line of feed with its right end directed rearwardly of the machine and is rotatable in a bearing in the machine frame. At the right end of the spreader shaft is clamped an arm 124 to the lower end of which is pivotally connected a link 126, in turn connected with a cam lever 128 engaging a cam on a shaft 130 rotating in unison with the main sewing shaft 58.

To provide sufficient time in each sewing cycle for operating the other stitch forming devices, particularly for looping the needle and for spreading each needle loop, the shuttle is accelerated as each beak receives a loop of thread and is decelerated after the loop carried thereby reaches a position of maximum extension. For this purpose the shuttle is driven through a variable speed device in addition to its speed reducing gear train. For driving the shuttle the driver gear 102 has three-quarters the number of teeth on the shuttle and is secured to a driver shaft 132 (see Fig. 4) having fixed to it a pinion 134 acting through a pair of serially meshing idler pinions 136 rotating on fixed stub shafts 138. The driver shaft 132 is rotatably mounted in bearings in the machine frame. The lower pinion 136 meshes with a driving spur gear 140 secured to a variable speed shaft 142 rotatable in the machine frame. The variable speed shaft 142 has its rearward end clamped in a block 144 forming a driven arm for a drag link connection. The arm 144 is actuated through a driving crank 146 by a drag link 148 pivotally connected between the arm 144 and the crank 146. The crank 146 is secured to a constant speed shaft 150 rotating at the same speed as the main sewing shaft 58, corresponding to the shaft 237 of the Gouldbourn et al. patent. The arrangement is such that the driver gear 102 which rotates the shuttle through $\frac{3}{4}$ of a revolution for each

rotation of the constant speed shaft 150 is located between the variable speed gear and the shuttle so that the variable speed drive brings each beak of the shuttle successively into a position to receive a loop of thread held spread by the loop spreader and needle uniformly at relatively low speed. After reception of a loop of thread each beak is accelerated to carry the loop of thread engaged thereby about the shuttle and the locking thread supply case 103 mounted within the shuttle.

The locking thread supply case 103 is of hollow cylindrical construction and has a grooved circular side wall and a rear end wall 152, the remaining forward end of the thread case being open to receive a supply of thread. One of the grooves 154 in the circular side wall forms a raceway for an internal rib on an annular split plate 156 attached to the rear of the shuttle for mounting the thread case rotatably within the shuttle (see Figs. 7 to 10, inclusive). In the other groove 158 of the thread case side wall is mounted an adjustable thread tension through which the thread passes on its way from a supply bobbin 160 toward the work. The supply bobbin 160 is grooved within the inner surface of its hub and is engaged by a pair of radially arranged spring-pressed plungers 162 mounted in a ferrule portion 164 of the thread case end wall. To guide the thread from the tension device, the thread case has a radial flange 166 projecting beyond its circular side wall into overlapping relation with a thread engaging portion of the shuttle and the flange is formed with a slot 168 and a guide eye 170 at the outer edge of the flange. As each loop of needle thread carried by the shuttle reaches a position where it is being freed from the shuttle, it is cammed out of engagement therewith by the flange on the thread case.

The locking thread tension device is located in the groove 158 of the thread case and comprises an arcuate tension spring 172 engaging at one end the thread as it passes axially along the circular side wall of the thread case, the thread entering an opening 173 from the bobbin 160. To anchor the spring 172, the other end is bent at right angles and enters a slot in the base of the groove 158 to keep the spring from sliding along the groove. The tension spring is retained in the groove 158 by an adjustable arcuate shield 174 having outwardly toed beveled ends entering oppositely disposed channels in the sides of the groove 158. The shield is retained in adjusted position along the groove 158 by the lateral pressure of one end of the shield remote from the tension spring which end is bifurcated to provide a yielding action. The solid end of the shield adjacent the tension spring overlies the spring and is movable along the spring in its retaining channel to press the spring more firmly against the thread running from the bobbin 160 or to reduce the pressure on the thread.

To enable the portion of the thread case against which the thread is pressed by the tension spring to be renewed readily after excessive wear without replacing the entire thread case, the thread engages a removable wear block 176 (Fig. 11) mounted for sliding movement axially along the thread case side wall. The wear block 176 is formed with an offset lug projecting radially from the circular side wall of the thread case to provide a surface flush with the outer surface on the flange of the thread case. The wear block 176 has a thread enclosing passage 178 and a slot

180 through which the thread is guided on its way to the guide eye 170 in the thread case flange. To introduce the thread between the wear block and the tension spring 172 when applying a new thread supply, the wear block has a tongue 182 disposed in the opening 173 opposite the thread engaging end of the tension spring. In applying the thread to the thread case the thread is inserted endwise through the passage 178 and is pressed between the tongue 182 and the spring 172 laterally through the opening 173 from the inside of the thread case so that when tension is applied to the thread it will be drawn between the tongue and the spring.

The slot 180 is located in the lug of the wear block 176 in such position that it is brought into alignment with the slot in the flange 166 of the thread case when the wear block is moved into position in the thread case side wall. To lock the wear block 176 in position it has grooves 183 along its outer surface disposed for alignment with the grooves 154, 158 of the thread case side wall so that when the tension spring 172 and the flange on the annular plate 156 fit into the grooves of the thread case they enter the grooves 183 on the block. The block has a dovetail section fitting correspondingly shaped surfaces in the thread case side wall to resist outward thrust. To lock the block against inward pressure radially of the thread case the offset lug on the block is provided with radially flaring side edges fitting within an opening of similar outline in the flange 166 of the thread case.

To prevent the thread case from rotating with the shuttle the thread case side wall is notched at 184 and is provided with a perforation 186 in its flange 166. Alternately engaging the notch and perforation are the hooked end of retainer members in the form of a finger 188 (see Figs. 2 and 3) and a pin 190 secured to levers 192 and 194, respectively. The mechanisms for actuating the retainer members comprise the levers 192 and 194 which are fulcrumed on a pin 196 mounted in a cover 198 for the driver gear 102. The hubs of levers 192 and 194 abut each other and are held from movement along the stud 196 by the inner surfaces of the cover 198. The upper ends of the levers 192 and 194 are slotted to carry rolls 200 engaging face cams 202 and 204 on the driver gear 102. The cams 202 and 204 are cut to cause the finger 188 and pin 190 to disengage and engage the thread case alternately in regular sequence as the needle loop moves about the thread case. To press the rolls 200 against their respective cams the forked portions of the levers are acted upon by coil springs 206 compressed between the levers and the inside surface of the cover 198.

The cover 198 is shown in Figs. 1, 2 and 3 and comprises a cup-shaped member provided with three lugs through which pass clamping screws 208 entering into threaded relation with the frame of the machine. For preventing entanglement of the teeth in the driver gear 102 within the cover 198 in case of thread breakage, the gear 102 is formed with an annular slot 210 (see Fig. 4) within which is disposed a thread repelling plate 212 (Fig. 3). The plate 212 is perforated and is clamped in place by one of the screws 208 which passes through the perforation between the cover and the frame. The plate has its leading end beveled at 214 to throw out threads or lint collecting in the slot 210.

To enable the bobbin readily to be removed from the thread case, the rear wall of the thread case

has an opening 216 through which passes the lower forwardly bent end of an ejector 217 having an upwardly extending handle in a readily accessible position. The ejector is fulcrumed on a slotted stud 218 fixed to the ejector and rotatable in a forked portion of the machine frame, within the fork of which the ejector moves. The slotted end of the stud is surrounded by the coils of a spring 220, one end of the spring being bent inwardly into the slot of the stud and the other end projecting outwardly to engage a pin on the forked portion of the machine frame. The spring 220 acts normally to hold the ejector away from the thread case so that each loop of needle thread may clear the ejector.

To insure escape of each needle loop from the beak of the shuttle which carries it, and to prevent the loop from being carried by the same or another beak a second time about the thread case, the flange 166 on the thread case has a flat outer surface and projects radially downwardly beyond the outer edge of the shuttle from the thread case. Beyond the flat surface of the flange it is beveled to enable each needle loop as it is carried about the thread case to move smoothly inwardly of the machine toward the work. The inner surface of the flange 166 is concave and fits closely with the outer forward convex surface of the shuttle with no substantial clearance between the parts. The lower left edge of the flange is formed with a gradual helix, the inclination of the flange edge to a radius of the thread case being greater than the inclination of the slots forming the shuttle beaks. With a flange having a lower edge of this shape each needle loop as it is carried about the shuttle is cammed away from engagement with its slot just as the beak formed thereby brings the needle loop to a proper releasing position.

To retain each needle loop within a slot of the shuttle at other times during rotation of the shuttle, the shuttle rotates within a two-part raceway plate 222 (see Fig. 3) fitting between the annular plate 156 and a similar plate 224 in which the beaks of the shuttle are formed. The raceway plate 222 extends from a position just beyond the point of entry for each needle loop into a slot behind a shuttle beak to a position at the other end of a cut-away section of the plate through which the needle loops are discharged.

To reduce the slack thread in each contracting needle loop 106 and to maintain control of the contracting loop of needle thread so that it will not be carried about the thread case by the shuttle a second time, the thread case retaining pin 190 is retained in engagement with the perforation in the flange 166 on the thread case until each contracting loop is definitely brought into engagement with it but the pin releases the thread before substantial tension is applied. The tension on the contracting thread loop, together with the cam surface on the lower edge of the flange, draws the loop out of engagement with the beak of the shuttle which carried it about the thread case (see Fig. 13), the thread being drawn through the work by the succeeding loop as it is carried over the shuttle at a rate faster than the movement of the shuttle beak.

To assist further in maintaining control and in preventing slack in each contracting loop of needle thread while it is being disengaged from the shuttle and while the whirl 8 is acting to lay the thread in the needle hook so that slight irregularities of timing or in lengths of thread in the loops will have no effect on the disengage-

ment of each loop of thread from the shuttle or otherwise in the formation of stitches, the flange 166 along its convex surface is engaged by an arcuate friction spring plate 226 secured at its upper end to a block 228 made fast to the frame of the machine. The lower end of the plate 226 overlies the slot 168 in the flange 166 and is provided with an elongated perforation 230 to enable the thread to be inserted in the slot while applying a new supply of thread to the case 103. The plate 226 also is formed with an opening to admit the retainer pin 190 into the opening 186 of the thread case. As each loop of thread reaches a position of maximum extension on the shuttle, its forward side slides between the end of the plate 226 and the flange 166. Continued rotation of the shuttle carries the loop downwardly toward the retainer pin 190, the loop being contracted by pulling the rearward side of the loop running behind the shuttle. Pulling the rearward side of the loop as it approaches the retainer pin causes the loop to be drawn downwardly clear of the shuttle beaks as illustrated in Fig. 13. When the loop engages the retainer pin it is positively released from engagement with the shuttle beak which carries it. In the meantime, the forward side of the contracting needle loop is detained frictionally in position between the plate 226 and the flange 166. After engagement with the retainer pin the contracting loop 106 slides easily from between the plate and the flange on the thread case and the pin is moved to free the loop, as illustrated in Fig. 14. Thereafter, the loop 106 with the encircled locking thread is drawn tightly into the work by the loop 104 in reaching its position of maximum extension (Fig. 15).

It will be noted that the tension and pull on the thread applied by the shuttle is in a direction to lift the work slightly from the tip of the horn 6. The pull on the thread is exerted on the work both by the retracting stroke of the needle and by the shuttle after the work has been fed at least a stitch length from the point at which the work is clamped by the presser foot 14 so that the portion of thread 108 connecting the stitch being formed with the preceding needle loop has reached a position where it will not be clamped against the upper end of the horn, the horn being cut away about the needle receiving opening at its upper end. The only other portion of thread engaging the horn is that running from the needle receiving opening to the stitch being formed. Due to the upward pull of the thread, this portion of thread also is freed from clamping engagement between the work and the horn, the work lifting sufficiently from the horn to free the thread.

One advantage of providing a shoe entering horn type sewing machine with actuating mechanisms wherein the work is fed by the needle while the shuttle is setting each stitch resides in improved uniformity with which each stitch is set in the work. This follows from the ample timing allotments in each sewing cycle for the feed to be accomplished while the needle engages the work, the feed having been completed before the awl penetrates the work for a new stitch. By completing the feed before each stitch is set the shuttle acts directly on the stitch being set instead of through an uncertain frictional resistance on the thread between the shuttle and the stitch being set, the clamping action on the thread against the work engaging surface of the horn being uncontrollable. By ar-

ranging the operation of the stitch forming devices in this manner, an improved sewing cycle results in which other motions imparted to the stitch forming devices may be accomplished with simple easily operated mechanisms in a manner not heretofore permissible by prior timing arrangements.

To reduce the amount of needle thread retracted through the work by the thread controller lever 110 and to measure sufficient thread from the supply to complete each stitch, a thread measuring device acting in accordance with the thickness of the work is provided and actuated to release its measured supply of thread to the thread controller after each needle loop has been engaged by the shuttle or loop taker. The thread measuring device acts on the thread between the thread controller 110 and a wax pot 232 (see Fig. 1) while the needle is being looped and comprises a pair of thread locks 234 and 236 between which the thread is engaged by a pull-off arm 238 (see also Fig. 24). The pull-off arm 238 is actuated by mechanism under the control of the presser foot while engaging the work, which mechanism is similar to the mechanism for actuating the pull-off lever 417 of Patent No. 2,331,118. The thread locks 234 and 236 are also actuated by mechanism similar to that employed by the thread locks 455 and 457 of that patent.

In the present machine, both thread locks are closed while each loop of needle thread is being drawn through the work by the needle. After the needle loop is spread and disengaged from the needle and loop spreader the front lock 234 is opened to release the measured thread, the thread pull-off arm 238 having already moved to provide slack thread between the thread locks. The thread controller retracts from the thread measuring device only a part of the thread required by one side of the needle loop as it is drawn through the work by the needle. The remainder of the thread retracted by the controller is furnished from the preceding needle loop being drawn over the shuttle beak as the beak enlarges each needle loop. Thus, the thread controller retracts thread from needle loops of two successive stitches.

When the machine comes to rest at the end of the seam a loop of thread, such as that indicated at 104 in Fig. 15, has reached a position of maximum extension on the shuttle and the previously formed stitch has been set in the work. Accordingly, before the work may be withdrawn from the machine it is necessary to sever the last-formed loop 104. If this loop is severed along its forward side close to the surface of the work, there will be a suitable length of thread drawn through the work in removing it from the horn to complete the first stitch of a new seam when the machine is restarted. The length of thread left remaining will be sufficient to enable a new loop in a seam to be drawn through the work by the needle and engaged with the shuttle, after which an additional length is provided by the thread measuring device corresponding in amount with the thickness of the new work piece introduced into the machine so that the end of the thread will be drawn into close proximity to the undersurface of the work as illustrated at 239 in Fig. 15.

In case a greater length of thread is required or the machine is to be rethreaded, thread may be drawn past the thread locks by releasing them manually. To release the thread locks, the mechanism for actuating them is connected to

a spring tensioned lever 240 fulcrumed on a stud 242 on the base of the machine and provided with a handle portion at its forward end in a conveniently accessible location. The lever 240 has an upwardly extending arm through which passes a threaded rod 244 having check nuts 245 disposed at opposite sides thereof and having a pivotal connection 248 with one arm of a bell crank 250 forming a part of the thread lock actuating mechanism. The lever 250 corresponds with a bell crank lever 483 of the Gouldbourn et al. patent and when rotated in one direction, opens both thread locks and when rotated in the other direction, closes them for operation in the usual way.

The operation of the stitch forming and work manipulating devices is most clearly indicated in Fig. 25. The work piercing and entering movements of the awl and needle are shown in the order noted by the first two curves of this figure with relation to a shaded band 252 indicating the maximum thickness of work intended to be operated upon by the machine. The needle remains in the work during the feeding movement and this feeding movement, illustrated in the third curve, may be adjusted between the maximum and minimum shown in solid and dotted lines respectively, the idle shift movement of the needle being the difference between the maximum and minimum feeding movements.

The presser foot lift and lock curves show a uniform work releasing movement of the presser foot from the work, the foot being unlocked at the end of its lifting movement, as shown in the fifth curve from the top of the figure, momentarily to enable the presser foot to accommodate itself to the thickness of the work. The significance of the remaining curves of Fig. 25 will be readily understood without extended explanation with the exception of that labeled "Shuttle."

The shuttle curve is made up in part of a dotted line and a solid line crossing each other in the neighborhood of 240°. The solid line represents the movements of one shuttle beak engaging a loop of needle thread and the dotted line forms a continuation of the solid line into the next succeeding cycle to illustrate the movements of the loop toward a position of maximum extension at 25° and then to illustrate the contracting movement of the loop. Each contracting loop remains on the shuttle beak until a new loop is engaged by another shuttle beak at approximately 220°, at which time two successive needle loops engage the shuttle simultaneously, each new loop drawing thread from the preceding loop. When a loop reaches a position of maximum extension on the shuttle the preceding loop is set in the material of the work.

The nature and scope of the invention having been indicated and a particular embodiment having been described, what is claimed is:

1. A shoe sewing machine having a work feeding hook needle, a rotary shoe entering horn and needle threading devices in the horn, in combination with mechanisms for actuating the needle including means to cause its threaded hook to be withdrawn from the horn into the substance of a shoe on the horn and means acting thereafter to cause the needle to be shifted with a work feeding movement the length of a stitch while engaging the shoe to feed the shoe.

2. A shoe sewing machine having a work feeding hook needle, a rotary shoe entering horn and needle threading devices in the horn, in

combination with mechanisms including means for actuating the needle to cause its threaded hook to be withdrawn from the horn into the substance of a shoe on the horn and means acting thereafter to cause the needle to be shifted the length of a stitch while still engaging the shoe to feed the shoe, and a needle engaging member acting close to the point of engagement of the needle with the shoe to reinforce the needle while being shifted to feed the shoe.

3. A sewing machine having a work feeding hook needle, needle threading and other stitch forming devices, in combination with mechanisms including means for actuating the needle to cause its threaded hook to be withdrawn from the threading device and means acting thereafter to cause the needle to be shifted the length of a stitch while still engaging the work.

4. A shoe sewing machine having a work feeding hook needle, a rotary shoe entering horn and needle threading devices in the horn, in combination with a carrier for the needle mounted for movement toward and from the work and in the direction of work feed, mechanisms including means for actuating the carrier to cause the threaded hook of the needle to be withdrawn from the threading device and to dwell while still engaging the work and means acting thereafter to cause the carrier to be shifted the length of a stitch while the needle is dwelling in the work, and a yielding needle engaging member on the needle carrier acting close to the point of engagement of the needle with the work while the carrier is being shifted in the direction of work feed to reinforce the needle.

5. A sewing machine having a curved work feeding hook needle, needle threading and other stitch forming devices, and a needle carrier arm, in combination with mechanisms for actuating the carrier arm to cause the threaded hook of the needle to be withdrawn from the threading device and thereafter to be shifted the length of a stitch while engaging the work to feed the work, and a needle engaging member pivoted to the carrier arm for movement along the needle to reinforce the needle during work feed.

6. A shoe sole sewing machine having an awl mounted for movement toward and from the work to pierce the work, and other stitch forming devices, in combination with a work feeding needle at the same side of the work with the awl, means for actuating the needle to enter each perforation formed in the work by the awl and means for actuating the needle with an idle lateral movement along the line of feed after it disengages the work to enable entry of the awl into the work a stitch length from the previously formed perforation.

7. A shoe sole sewing machine having an awl mounted for movement toward and from the work to pierce the work, and other stitch forming devices, in combination with a work feeding needle spaced at a distance from the awl along the line of feed at least the length of a stitch, means for actuating the needle to enter the perforation formed in the work by the awl and means for actuating the needle with an idle lateral movement in the direction of work feed after it disengages the work to enable entry of the awl into the work a stitch length from the previously formed perforation.

8. A shoe sole sewing machine having an awl mounted for movement toward and from the work to pierce the work, and other stitch forming devices, in combination with a work feeding

needle mounted for movement with a fixed spacing along the line of feed between the awl and the needle at least the length of a stitch and mechanism for actuating the needle with an idle lateral movement in the line of feed after being disengaged from the work to enable the awl to be moved to a point within a stitch length of the previously formed perforation.

9. A shoe sole sewing machine having an awl mounted for movement toward and from the work to pierce the work, and other stitch forming devices, in combination with a work feeding needle mounted for movement with a fixed spacing along the line of feed between the awl and the needle, and mechanism for actuating the needle with an idle lateral movement along the line of feed after being disengaged from the work to enable the awl to be moved a stitch length from the previously formed perforation.

10. A shoe sole sewing machine having an awl mounted for movement toward and from the work to pierce the work, and other stitch forming devices, in combination with a work feeding needle mounted for movement with a fixed spacing along the line of feed between the awl and the needle, mechanism for actuating the needle with an idle lateral movement along the line of feed after being disengaged from the work to enable the awl to be moved a stitch length from the previously formed perforation, and adjustable mechanism for actuating the needle along the line of feed while in engagement with the work.

11. A shoe sole sewing machine having an awl mounted for movement toward and from the work to pierce the work, and other stitch forming devices, in combination with a work feeding needle mounted for movement with a fixed spacing along the line of feed between the awl and the needle, mechanism for actuating the needle with an idle lateral movement along the line of feed after being disengaged from the work to enable the awl to be moved a stitch length from the previously formed perforation, adjustable mechanism for actuating the needle along the line of feed while in engagement with the work, said mechanisms comprising a pair of levers and cams, a pair of links connected to the respective levers and a central needle actuating pivot connecting the links.

12. A shoe sole sewing machine having an awl mounted for movement toward and from the work to pierce the work, and other stitch forming devices, in combination with a work feeding needle mounted for movement with a fixed spacing along the line of feed between the awl and the needle, mechanism for actuating the needle with an idle lateral movement along the line of feed after being disengaged from the work to enable the awl to be moved a stitch length from the previously formed perforation, adjustable mechanism for actuating the needle along the line of feed while in engagement with the work, said mechanisms comprising a pair of levers and cams, a pair of links connecting the respective levers, a central pivot connecting the links, and a single link operatively connecting the central pivot to the needle.

13. A shoe sole sewing machine having an awl mounted for movement toward and from the work to pierce the work, and other stitch forming devices, in combination with a work feeding needle mounted for movement with a fixed spacing along the line of feed between the awl and the needle, mechanism for actuating the needle with an idle lateral movement along the line of

feed after being disengaged from the work to enable the awl to be moved a stitch length from the previously formed perforation, adjustable mechanism for actuating the needle along the line of feed while in engagement with the work, said mechanisms comprising a pair of levers and cams, and a pair of links connected to the respective levers, a central needle actuating pivot connecting the links, the link of the adjustable mechanism being connected to its lever by an arcuate slot and clamping stud and the arcuate slot being formed concentrically with the central pivot while the needle is in its fully fed position.

14. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed while being retained with a uniform spacing between each other, and means for retaining the needle and awl carriers in engagement with each other.

15. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed while being retained with a uniform spacing between each other, means for retaining the needle and awl carriers in engagement with each other comprising a spindle passing through the needle and awl carrier arms, and clamping means on the spindle for the carrier arms.

16. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed, means for retaining the needle and awl carriers in positions comprising an eye-headed spindle passing through the needle and awl carriers, and feeding mechanism having a pivot passing through the eye in the spindle.

17. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed while being retained with a uniform spacing between each other, means for retaining the needle and awl carriers in positions comprising a spindle passing through the needle and awl carriers, sleeves surrounding the spindle within the needle and awl carriers, one of said sleeves being internally threaded to engage threads on the spindle, and means for clamping the sleeves to the spindle.

18. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed while being retained with a uniform spacing between each other, means for retaining the needle and awl carriers in positions comprising

a spindle passing through the needle and awl carriers, sleeves surrounding the spindle within the needle and awl carriers, one of said sleeves being internally threaded to engage threads on the spindle, and a member between the carriers for rotating the threaded sleeve on the spindle.

19. A shoe sewing machine having a curved work piercing awl and a curved work penetrating needle at the same side of the work, the needle acting to enter a perforation formed by the awl, carrier arms for the needle and awl mounted to oscillate about the same axis toward and from the work and to move in the line of feed while being retained with a uniform spacing between each other, means for retaining the needle and awl carriers in positions comprising a spindle passing through the needle and awl carriers, sleeves surrounding the spindle within the needle and awl carriers, one of said sleeves being internally threaded to engage threads on the spindle, a member between the carriers for rotating the threaded sleeve on the spindle, and a check nut on one end of the spindle for clamping the other sleeve and rotating member to the threaded sleeve.

20. A shoe sewing machine having a work feeding hook needle, a rotary shoe supporting horn having a needle receiving opening at its end, a presser foot cooperating with the work supporting horn to clamp a shoe opposite the shoe engaging surface of the horn at a position in advance of the needle, and needle threading devices at the end of the horn in alignment with the opening, in combination with mechanism for actuating the needle to cause its threaded hook to be withdrawn from the opening in the horn while in alignment therewith into the substance of the shoe to clear the horn, and means for causing the needle thereafter to be shifted laterally the length of a stitch from alignment with the opening in the horn while engaging the shoe.

21. A shoe sewing machine having a work feeding hook needle, a rotary work supporting horn, a presser foot cooperating with the work supporting horn to clamp the work opposite the work engaging surface of the horn and needle threading devices in the horn, in combination with mechanism for actuating the needle to cause its threaded hook to be withdrawn from the horn into the substance of the shoe and thereafter to be shifted from the presser foot the length of a stitch while engaging the shoe, and a needle engaging member acting against the presser foot close to the point of engagement of the needle with a shoe to reinforce the needle while being shifted to feed the shoe.

22. A shoe sewing machine having stitch forming devices including a hook needle, and a thread controller acting during its full stroke to furnish less than half the thread needed from the time the needle is threaded until it reaches the end of its movement away from a shoe, a work support and a presser foot, in combination with a multiple beak loop taker at the side of the work with the needle arranged to receive a loop of thread from the needle with one beak while another beak retains the previously formed loop of thread.

23. A shoe sewing machine having stitch forming devices including a hook needle, a work support and a presser foot, in combination with a multiple beak loop taker at the side of the work with the needle arranged to receive a loop of

thread from the needle with one beak while another beak retains the previously formed loop of thread, a gear train for driving the loop taker less than a complete rotation during each sewing cycle to cause each beak on the loop taker to be brought into position for reception of a loop of thread from the needle in regular sequence, and a variable speed device for driving the gear train to accelerate the loop taker as each beak receives a loop of thread and to decelerate the loop taker after the loop of thread carried thereby reaches a position of maximum extension.

24. A shoe sewing machine having stitch forming devices including a hook needle, and a thread controller acting during its full stroke to furnish less than half the thread needed from the time the needle is threaded until it reaches the end of its movement away from a shoe, a rotary work supporting horn at the opposite side of the work from the needle, said horn having a needle receiving opening at its end, a needle threading device at the end of the horn in alignment with the needle opening, and a presser foot at the side of the work with the needle for clamping the work against the horn, in combination with a multiple beak loop taker at the side of the work with the needle arranged to receive a loop of thread from the needle with one beak while another beak retains control of the previously formed loop of thread.

25. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains control of the previously formed loop of thread, and means for driving the loop taker at a variable speed with respect to the operation of the other stitch forming devices.

26. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains control of the previously formed loop of thread, means for driving the loop taker comprising connections acting at a ratio other than one to one, and a variable speed device for driving said connections to cause each beak on the loop taker to be brought into position for reception of a loop of thread from the needle in regular sequence and to be accelerated and decelerated with respect to the point at which the loop is received in a uniform manner.

27. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains con-

control of the previously formed loop of thread, a gear train for driving the loop taker less than a complete rotation during each sewing cycle, and a drag link device for driving the gear train to accelerate the loop taker as each beak receives a loop of needle thread and to decelerate the loop taker after the loop of thread carried thereby is enlarged to a position of maximum extension.

28. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains control of the previously formed loop of thread, means for driving the loop taker comprising connections acting at a ratio other than one to one, a variable speed device for driving said connections to cause each beak on the loop taker to be brought into position for reception of a loop of thread from the needle in regular sequence and to be accelerated and decelerated with respect to the point at which the loop is received in a uniform manner, and a friction plate to prevent slack thread in the loop carried thereby while it is being disengaged from the loop taker.

29. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains control of the previously formed loop of thread, a gear train for driving the loop taker less than a complete rotation during each sewing cycle to cause each beak on the loop taker to be brought into position for reception of a loop of thread from the needle in regular sequence, a variable speed device for driving the gear train to accelerate the loop taker as each beak receives a loop of thread and to decelerate the loop taker after the loop of thread carried thereby reaches a position of maximum extension, and a friction plate acting on the thread beyond the position of maximum extension of the loop to prevent slack thread while the needle threading device is acting to lay the thread in the needle hook.

30. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, and means rotating with the driver gear for causing the thread case to be retained against rotation with the shuttle.

31. A shoe sewing machine having stitch forming devices including a hook needle, a rotary work supporting horn at the opposite side of the work

from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, a cam rotating with the driver gear, and a member actuated by the cam and arranged to engage the thread case to retain it against rotation with the shuttle, said driver gear and the teeth on the shuttle having a driving ratio proportional to the number of beaks in the shuttle less one to the whole number of beaks on the shuttle.

32. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, cams rotating with the driver gear, levers actuated by the cams, and thread case engaging members operatively connected to the levers to retain the thread case against rotation with the shuttle.

33. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, cams rotating with the driver gear, levers actuated by the cams, and thread case engaging members operatively connected to the levers to retain the thread case against rotation with the shuttle, one of said cams being constructed to actuate one member away from the thread case after a loop of needle thread has been engaged with said one member during each sewing cycle.

34. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, cams rotating with the driver gear, levers actuated by the cams, and thread case engaging members operatively connected to the levers to retain the

thread case against rotation with the shuttle, one of said cams being cut to actuate a member to clear the loop of needle thread carried by the shuttle as the loop approaches a position of maximum extension and another of said cams being cut to actuate a second member after the loop of thread has been slackened by the shuttle and engaged with said second member.

35. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak deep tooth shuttle at the side of the work with the needle arranged to receive a loop of thread from the needle with one beak while another beak retains control of the previously formed loop of thread, a locking thread case about which the shuttle carries each loop of needle thread, a driver gear engaging the teeth of the shuttle, cams rotating with the driver gear, levers actuated by the cams, thread case engaging members operatively connected to the levers to retain the thread case against rotation with the shuttle, one of said cams being cut to actuate a member to clear the loop of needle thread carried by the shuttle as the loop approaches a position of maximum extension and another of said cams being cut to actuate a second member after the loop of thread has been slackened by the shuttle and engage with said second member, and a frictional member cooperating with the thread case to prevent slack thread in the loop carried by the loop taker while the loop is being disengaged from the beak in which said loop was carried.

36. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains the previously formed loop of thread, a locking thread case about which the shuttle carries each loop of needle thread, and a flange on the thread case for camming each loop carried by the shuttle out of the beak to prevent the loops from being carried a second time about the thread case.

37. A shoe sewing machine having stitch forming devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains the previously formed loop of thread, a locking thread case about which the shuttle carries each loop of needle thread, a flange on the thread case for camming each loop carried by the shuttle out of the beak to prevent the loops from being carried a second time about the thread case, and a friction plate cooperating with a flange on the thread case to prevent slack thread while each loop is being cammed out of its beak by the flange on the thread case.

38. A shoe sewing machine having stitch form-

ing devices including a hook needle, a rotary work supporting horn at the opposite side of the work from the needle, a needle threading device in the horn, and a presser foot at the side of the work with the needle for clamping the work against the horn, in combination with a multiple beak loop taker at the side of the work with the needle arranged to receive a loop of thread from the needle with one beak while another beak retains the previously formed loop of thread, a locking thread case about which the shuttle carries each loop of needle thread, a flange on the thread case for camming each loop carried by the shuttle out of the beak to prevent the loops from being carried a second time about the thread case, a friction plate cooperating with the flange on the thread case to prevent slack thread while each loop is being cammed out of its beak by the flange on the thread case, and a retainer acting on the thread case in proximity to the flange to be engaged by the thread in a loop to cause the loop to be drawn clear of the beak on the shuttle which carried it about the thread case and thereafter to be disengaged from the shuttle.

39. A shoe sewing machine having stitch forming devices including a hook needle, a work support, a needle threading device, a presser foot for clamping the work against the work support, and a loop taker, in combination with a locking thread supply case about which the loop taker passes each loop of needle thread, and a flange on the thread case having a helical edge for camming each loop of thread away from the loop taker.

40. A shoe sewing machine having stitch forming devices including a hook needle, a work support, a needle threading device, a presser foot for clamping the work against the work support, and a loop taker, in combination with a locking thread supply case about which the loop taker passes each loop of needle thread, a flange on the thread case having a helical edge for camming each loop of thread away from the loop taker, and a friction plate cooperating with the flange on the thread case to prevent slack thread while each loop is being disengaged from the loop taker.

41. A shoe sewing machine having stitch forming devices including a hook needle, a work support and a presser foot, in combination with a multiple beak loop taker at the side of the work with the needle arranged to receive a loop of thread from the needle with one beak while another beak retains the previously formed loop of thread, and a thread controller for paying out thread to the needle while the threaded needle is being drawn through the work.

42. A shoe sewing machine having stitch forming devices including a hook needle, a work support and a presser foot, in combination with a multiple beak loop taker at the side of the work with the needle arranged to receive a loop of thread from the needle with one beak while another beak retains the previously formed loop of thread, a loop spreader for opening each loop of needle thread for the loop taker, and a thread controller for paying out thread to the needle while the threaded needle is being drawn through the work and for terminating the thread yielding movement thereafter.

43. A shoe sewing machine having stitch forming devices including a hook needle, a work support and a presser foot, in combination with a multiple beak loop taker at the side of the work with the needle arranged to receive a loop of thread from the needle with one beak while another beak retains the previously formed loop of

thread, a loop spreader for opening each loop of needle thread for the loop taker, a thread controller for paying out thread to the needle while the threaded needle is being drawn through the work and for terminating the thread yielding movement thereafter, and mechanism for actuating the controller to retract thread from the needle loop while the loop taker engages said loop.

44. A shoe sewing machine having stitch forming devices including a hook needle, a work support and a presser foot, in combination with a multiple beak loop taker at the side of the work with the needle arranged to receive a loop of thread from the needle with one beak while another beak retains the previously formed loop of thread, a loop spreader for opening each loop of needle thread for the loop taker, a thread controller for paying out thread to the needle while the threaded needle is being drawn through the work and for terminating the thread yielding movement thereafter, and mechanism for actuating the controller to retract thread from the needle loops of two successive stitches while the last-formed needle loop is engaged by the loop taker.

45. A shoe sewing machine having stitch forming devices including a hook needle, a work support and a presser foot, in combination with a multiple beak loop taker at the side of the work with the needle arranged to receive a loop of thread from the needle with one beak while another beak retains the previously formed loop of thread, and a thread measuring device connected for actuation in timed relation to the operations of the other stitch forming devices for releasing thread to the other stitch forming devices after each needle loop has been engaged by the loop taker.

46. A shoe sewing machine having stitch forming devices including a hook needle operating toward and from the work, a work support and a presser foot, in combination with a multiple beak loop taker at the side of the work with the needle arranged to receive a loop of thread from the needle with one beak while another beak retains the previously formed loop of thread, a thread controller, and a thread measuring device connected for actuation in timed relation to the operations of the other stitch forming devices to release thread to the thread controller after the threaded needle has withdrawn from the work.

47. A shoe sewing machine having stitch forming devices including a hook needle operating downwardly toward and upwardly from the work, a work support and a presser foot, in combination with a multiple beak loop taker at the side of the work with the needle arranged to receive a loop of thread from the needle with one beak while another beak retains the previously formed loop of thread, a thread controller, and a thread measuring device acting to release thread to the thread controller after the threaded needle has withdrawn from the work, said thread controller only paying out one-half the thread needed from the time the needle is looped until it reaches the top of its stroke.

48. A shoe sewing machine having stitch forming devices including a hook needle operating toward and from the work, a work support and a presser foot, in combination with a multiple beak loop taker at the side of the work with the needle arranged to receive a loop of thread from the needle with one beak while another beak re-

tains the previously formed loop of thread, a thread controller, a thread measuring device acting to release thread to the thread controller after the threaded needle has withdrawn from the work, and mechanism for actuating the thread controller to retract an amount of thread equal to one side only of the needle loop while on the loop taker.

49. A shoe sewing machine having stitch forming devices including a hook needle operating toward and from the work, a work support and a presser foot, in combination with a multiple beak loop taker at the side of the work with the needle arranged to receive a loop of thread from the needle with one beak while another beak retains the previously formed loop of thread, a thread controller, a thread measuring device acting to release thread to the thread controller after the threaded needle has withdrawn from the work, mechanism for actuating the thread controller with a stroke sufficient only to furnish less than half the thread needed from the time the needle is looped until it reaches the end of its movement away from the work to retract thread from the needle loop on the loop taker, and mechanism for actuating the thread measuring device to measure thread from the supply while the needle is being looped.

50. A shoe sewing machine having stitch forming devices including a hook needle and a circular shuttle including a thread engaging portion at the side of the work with the needle, a work support and a presser foot, in combination with a locking thread case within the shuttle having a flange overlapping the thread engaging portion of the shuttle, the flange being arranged to cam each loop carried by the shuttle out of engagement therewith.

51. A shoe sewing machine having stitch forming devices including a hook needle and a deep tooth circular shuttle, a work support and a presser foot, in combination with a locking thread case within the shuttle having a flange extending radially beyond the outer edge of the shuttle for camming each loop carried by the shuttle out of engagement therewith.

52. A shoe sewing machine having stitch forming devices including a hook needle and a deep tooth circular shuttle, a work support and a presser foot, in combination with a locking thread case within the shuttle having a flange extending radially beyond the outer edge of the shuttle for camming each loop carried by the shuttle out of disengagement therewith, and a friction plate cooperating with the flange on the thread case to prevent slack thread in each needle loop as it is being cammed away from the shuttle by the flange on the thread case.

53. A shoe sewing machine having stitch forming devices including a hook needle and a deep tooth circular shuttle, a work support and a presser foot, in combination with a locking thread case within the shuttle having a flange extending radially beyond the outer edge of the shuttle for camming each loop carried by the shuttle out of disengagement therewith, a thread case retainer for preventing rotation of the thread case with the shuttle acting on the flange to engage the thread in a loop as the loop reaches a position to be cammed away from the shuttle, and mechanism for actuating the retainer to release the loop before substantial tension is applied thereto.

54. A hollow cylindrical locking thread case for a lockstitch shoe sewing machine having a grooved circular side wall and an end wall, the remaining

end of the thread case being open to receive a supply of thread, and a thread tension spring fitting within the groove of the side wall and acting radially of the circular side wall against the base of the groove, in combination with a removable wear block of dovetail section mounted for sliding movement axially of the thread case and provided with a groove disposed for alignment with the groove of the thread case wall to cause the wear member to be held in place by the tension spring within the alined grooves.

55. A hollow cylindrical locking thread case for a lockstitch shoe sewing machine having a circular side wall grooved to provide a raceway for mounting the thread case and for providing a tension slot running about the thread case and an end wall, the remaining end of the thread case being open to receive a supply of thread, a thread tension spring fitting within the tension slot and acting radially of the circular side wall against the base of the slot, in combination with a removable wear block of dovetail section mounted for sliding movement axially of the thread case, and provided with grooves disposed for alignment with the grooves of the thread case wall to cause the wear member to be locked in position by the tension spring within the alined grooves of the tension slot.

56. A hollow cylindrical locking thread case for a lockstitch shoe sewing machine having a grooved circular side wall and an end wall, the remaining end of the thread case being open to receive a supply of thread, and a thread tension spring fitting within the groove of the side wall and acting radially of the circular side wall against the base of the groove, in combination with a removable wear block of dovetail section mounted for sliding movement axially of the thread case and provided with a groove disposed for alignment with the groove of the thread case wall to cause the wear member to be held in place by the tension spring within the alined grooves, and a tongue on the wear block against which the tension spring acts and between which and the spring the thread is pressed laterally from the inside of the thread case.

57. A shoe sewing machine having stitch forming devices including a hook needle, a shuttle and a cylindrical locking thread case within the shuttle having a circular side wall, a radial flange projecting beyond the side wall and an end wall, the remaining end of the thread case being open to receive a supply of thread, in combination with a removable wear block mounted for sliding movement axially along the thread case side wall and formed with a lug projecting radially of the thread case with its surface flush with the outer surface on the flange of the thread case, and means for guiding the thread from the thread case along the lug and flange comprising alined slots in the lug and flange.

58. A shoe sewing machine having a work feed-

ing hook needle, a rotary shoe entering horn having a needle receiving opening, a presser foot to clamp the work against the horn, a needle threading device in the horn beneath the opening, a loop taker acting to pass a loop of needle thread about a supply of locking thread and to set each previously formed stitch, and mechanism for actuating the presser foot comprising means to clamp the work securely against the horn while each stitch is being set in combination with mechanisms for actuating the needle lengthwise to cause its threaded hook to be withdrawn from the needle receiving opening in the horn into the substance of a shoe on the horn and thereafter before each stitch is set to be shifted laterally away from the needle receiving opening in the horn the length of a stitch while being detained in engagement with the shoe with a shoe feeding movement.

59. A shoe sewing machine having a work feeding hook needle, a rotary shoe entering horn, a presser foot to clamp the work against the horn, a needle threading device in the horn, a multiple beak loop taker acting to pass a loop of needle thread about a supply of locking thread and to set each previously formed stitch, and mechanism for actuating the presser foot comprising means to clamp the work securely against the horn while each stitch is being set and means to lock the presser foot in work clamping position, in combination with mechanisms for actuating the needle to cause its threaded hook to be withdrawn from the horn into the substance of a shoe on the horn, then to be shifted away from the horn the length of a stitch while engaging the shoe with a shoe feeding movement and thereafter to retract from the shoe with a needle loop, one side of which is furnished by contracting a previously formed loop of thread in the shoe, one of said needle feeding mechanisms actuating the needle to carry the thread between the stitch being formed and the previously formed stitch clear of the horn where a substantial reduction is obtained in frictional engagement of the thread with the horn during contraction of the previously formed loop of thread.

FRED ASHWORTH.
JOSEPH R. IOANNILLI.
